CENTRIFUGE MACHINE

Albert Peltzer, Sr., San Francisco, Calif., assignor
to Merco Centrifugal Co., San Francisco, Calif.,
a corporation of California

Application March 8, 1950, Serial No. 148,411

5 Claims. (Cl. 233—21)

1

This invention relates generally to centrifuge machines and methods adapted particularly for the continuous separation of components from a fluid feed material.

In certain types of continuous centrifuges the amount of material discharging with the centrifugally separated underflow is greatly augmented by the use of a supplemental fluid material, as for example by continuously returning a large proportion of the underflow back into the centrifuge rotor. A centrifuge of this type is disclosed and claimed in Peltzer 1,923,454. The augmented discharge is desirable for certain reasons, including particularly minimizing the possibility of plugging or clogging of the discharge nozzles. Such centrifuges have certain inherent difficulties, particularly in that the discharge from the rotor must be handled in such a manner as to avoid undue power loss, and care must be taken to avoid undue spilling of discharge material into portions of the housing where it is not desired, and splash-back of such spill against the fast running rotor. Undue power consumption can be avoided to a substantial degree by the use of backwardly reacting jets such as disclosed in Patents 1,847,751 and 2,060,239. Nozzles forming backwardly reacting jets will not eliminate objectionable spill, even when the discharge from the nozzles is received by a volute such as disclosed in Patent 2,060,239.

In addition to the foregoing it is frequently desirable to deliver the underflow material to a tank or other piece of equipment located a considerable height above the centrifuge. The use of a discharge volute such as disclosed in Patent 2,060,239 will develop a pressure head for discharge of the underflow at an elevation above the centrifuge, but in many instances greater pressure heads are desirable to facilitate discharge of the underflow to greater elevations. A relatively high pressure head in the volute is also desirable in that it facilitates operation at high underflow gravity, without causing clogging of the piping through which the underflow material may be conducted from the volute.

Because of the power losses which occur in a centrifuge of the above character, considerable heating takes place which in some instances may cause injury to heat sensitive material. Cooling means incorporated in the rotor construction is necessarily relatively complicated and expensive, and in general is not satisfactory for most commercial applications. It is also desirable in some instances to regulate the temperature of the material undergoing treatment, as for example to

2

maintain the material at an elevated temperature, or to maintain it at a relatively low or subnormal temperature. Here again the heat transfer means used in the past have not been satisfactory for such continuous commercial machines.

It is an object of the present invention to generally improve upon centrifuges and methods of the above character, particularly with respect to the means employed for receiving the discharge of underflow material.

It is another object of the invention to provide an improved centrifuge and method of the above character having relatively efficient means for receiving the underflow material discharged from the rotor, and which serves to develop a relatively high pressure head for delivery of the underflow material to any point desired.

Another object of the invention is to provide an improved centrifuge of the above character having improved means for receiving and handling the underflow material, and which facilitates the discharge of a high gravity underflow.

Another object of the invention is to provide a machine of the above character having improved means for receiving the underflow discharge whereby power consumption is reduced and spill from the underflow volute is minimized.

Another object of the invention is to provide an improved means and method for effecting a heat transfer to or from the material being treated, whereby in the operation of the machine overheating can be prevented, or the material may be heated or cooled to a desired temperature level.

Additional objects and features of the invention will appear from the following description in which the preferred embodiment has been set forth in detail in conjunction with the accompanying drawing.

Referring to the drawing—

Figure 1 is a side elevational view partly in section showing a machine incorporating the present invention.

Figure 2 is a diagrammatic plan view showing connection for the return of discharge material to the rotor, for removal of discharge material and for introduction of wash liquor.

Figure 3 is a sectional detail showing the upper portion of the rotor and adjacent parts which provide for the discharge of overflow.

Figure 4 is a detail view in plan showing the so-called pickup ring at the lower end of the rotor section 10c.

Figure 5 is a diagram schematically illustrating

the machine of Figure 1 and showing external connections for a return circuit which includes a vent box.

Figure 6 is a cross-sectional detail illustrating another embodiment of the invention.

Figure 7 is a cross-sectional detail taken along the line 7—7 of Figure 6.

Figure 8 is a cross-sectional detail like Figure 6, illustrating another embodiment of the invention.

Figure 9 is a cross-sectional detail taken along the line 9—9 of Figure 8.

Figure 10 is a schematic view illustrating connections to a centrifuge having heat exchange means such as illustrated in Figure 8.

Figure 11 is a cross-sectional detail similar to Figure 9 and illustrating an arrangement for draw-off of underflow material from between two adjacent vanes.

The centrifuge illustrated in the drawing consists generally of a rotor 10 carried by the vertical shaft 11, and disposed within the stationary housing 12. As will be presently described the rotor is provided with various passages, including a passage for inflow of fluid feed material, a passage for discharge of lighter centrifugally separated overflow, and a passage for introducing a supplemental fluid material which is preferably made up of the heavier centrifugally separated discharge material. Rotor shaft 11 is connected by coupling 13 to the vertical shaft 14 of an electric motor 16. This motor is suitably supported upon a mounting ring 17 and carries the necessary bearings to maintain the rotor shaft in proper alignment. Ring 17 is carried upon the upper end of a supporting shell 18, which in turn is secured to the rotor housing 12. Ring 17 is cushioned by the compression springs 19, and is retained against displacement by screws 21.

Housing 12 is preferably made in a plurality of sections normally bolted together, and which when separated permit access to or removal of the rotor. Thus in the particular construction illustrated there are two main upper and lower housing sections 12a and 12b which form the space 24 for accommodating the rotor 10. Normally these sections are held together by screws 26 in conjunction with clamps 27.

The body of the rotor 10 is likewise preferably made of a number of annular parts including in this instance the main part 10a, and upper and lower conical shaped parts 10b and 10c. Part 10a has an inner portion 28 which is attached to the lower end of the rotor shaft 11. Parts 10a and 10b are retained together by suitable means such as the expansible clamping ring 29. Within the main chamber 30 of the rotor there is a group of spaced separating discs 31 such as are commonly used in centrifuges. Mounted within the outer peripheral wall of the main body part 10a, are the circumferentially spaced nozzles 32, each of which is provided with a discharge orifice 33 directed backwardly with respect to the direction of rotation. A suitable type of nozzle structure is disclosed in Patent 2,060,239.

Disposed inwardly of the set of discs 31 there is a sleeve-like member 34 which is downwardly divergent, and which has a lower flared portion 36 underlying the lowermost separating disc. The inner wall of member 34 is provided with circumferentially spaced vanes 37, and these vanes extend from the lower side of the flared portion 36. Member 34 forms a passage 38 for receiving fluid feed material, and this passage connects with the main chamber 30 through the

passage 39 formed between flared portion 36, and the adjacent wall of portion 28.

The lower portion of the rotor forms an impeller 41 for the return of underflow material 5 back into the rotor. Briefly this impeller is formed by the body part 10c which has an axial opening 42 in its lower end for receiving discharge underflow material. Circumferentially spaced vanes 43 are disposed within body part 10c, and serve to impart rotational velocity to material delivered into the impeller, with discharge of material through the radially extending passages 44 into the annular space 45 surrounding the outer portion of separating chamber 30. Passages 44 are formed between the inner wall of body part 10a, and an inner conical shaped member 46. Walls or vanes 47 are interposed between member 46 and the adjacent wall of body part 10a, whereby as the material passes through the passages 44 it must be at a rotational velocity approximating that of the rotor at the time of its discharge. The annular chamber portion 45 into which the material discharges from passages 44 is connected to the main separating chamber through the annular orifice 49.

The lower housing section 12b is formed to provide a volute 51, which is disposed generally in a plane at right angles to the axis of the rotor 30 and substantially aligned with the plane of the nozzles 32. The volute passage can be substantially circular as viewed in plan, or it may be spirally contoured like the volute of a centrifugal pump. It communicates with a tangential discharge conduit 52. In the arrangement shown in Figure 2 conduit 52 is connected to the pipe bend 53, which in turn connects with the fitting 54 at the bottom of the housing. Material returned through pipe 53 passes upwardly into the impeller 41 through the nozzles 56. An additional valve controlled pipe 58 is shown for removing underflow material from the machine, and a pipe 59 is provided for introducing an additional wash liquid, such as fresh water. It is necessary to maintain a desired pressure head in the return circuit. This is accomplished by proportioning the orifice opening through the nozzle 56. With proper proportioning of this nozzle the return material is jetted through the nozzle into the impeller 41 and a desired pressure head is maintained in the pipes 52, 53 and in the volute 51.

Instead of providing a direct return as in Figure 2, the return can be by way of another piece of equipment, such as a flotation cell 61 (Figure 5). Pipe 62 is shown delivering material from the volute to the cell 61, and from this cell material flows back by way of line 63 to the centrifuge rotor. Line 64 represents a draw-off from flotation cell 61, and line 65 represents introduction of a wash liquor such as fresh water. The fresh water is introduced in such a manner as to secure intimate mixing with the material being returned by pipe 63.

So-called throat rings 67 and 68 are interposed 65 between the nozzles 32 and the volute passage 51. These rings are spaced apart to provide the annular throat passage 69. The inner portion of the throat passage 69 is adjacent the nozzles 32 and is dimensioned to adequately receive the jets of material issuing from the nozzle orifices 33. The outer portion of the throat passage forms an annular orifice or passage 71, through which the material passes from the throat to the 70 volute passage 51. The lower throat ring 68 can

be sloped downwardly from the nozzles 32 to the throat passage 51 as illustrated, whereby when the machine is not in normal operation, any liquid received upon the throat ring 68 from nozzles 32 tends to flow by gravity into the volute passage 51. If desired the angle to which ring 68 is sloped may be increased beyond the angle shown.

When it is desired to repair or change the rotor, the upper housing section 12a is released from the lower section, whereby it can be lifted vertically together with the rotor to permit access to the working parts. For this purpose the inner edge 72 of the throat ring 67 is slightly larger in diameter than the diameter swept by the outer end of nozzles 32, thus permitting the nozzles to pass upwardly through the throat ring 67. To extend the effective length of throat ring 67 inwardly, the upper housing section 12a is fitted with a sheet metal member 73, the lower edge of which as an inturned flange 74 which normally extends inwardly from the throat ring edge 72.

The upper and inner portion of member 73 also forms a part of a seal about the upper end of the rotor. Thus the upper end of the rotor is provided with a ring 76, which is formed to provide an annular and inwardly faced recess 77. This recess is provided with a series of circumferentially spaced vanes 75. Extending downwardly from the top of the housing there is a tube 78, having an outwardly turned or flared lower end portion 79, which is disposed within recess 77. Portion 79 includes the substantially parallel annular wall portions 81 and 82. Between these wall portions are the vanes 83 which deflect liquid inwardly and upwardly.

The lighter centrifugally separated overflow discharges between vanes 83 and through the passage 84 into the chamber 85 from which it is withdrawn. Space 86 of the housing overlies chamber 85 and is in communication with passage 38 and the space 87 about member 34.

Previous reference has been made to the picking up of whatever small amount of the material may find its way into the lower part of the housing. Any material finding its way into the lower housing section 12b accumulates in the annular space 88 surrounding the nozzle 56. The lower end of the impeller is provided with what can be termed a pick-up ring 91, which is in relatively close proximity with the upper end of nozzle 56. This pick-up ring is provided with arcuate vanes 92 (Figure 4) whereby any material finding its way into space 88 is picked up by the action of ring 91 and delivered back into the rotor together with the returned material. The vanes extend inwardly and are separated by slots 93. Their leading portions 94 are bent downwardly to engage and urge fluid material upwardly.

To facilitate supplying a feed to the machine a conduit 90 is mounted upon the upper housing section 12a and communicates with the upper end of a passage 89 which is provided about the rotor shaft 11 and extends downwardly within member 34. Within member 34 the shaft is shrouded by the sleeve 97. The feed material can be received from a pipe 95 and screen 98.

Operation of my machine can be described as follows: The rotor is driven at a suitable speed, such as the order of from 5,000 to 10,000 R. P. M. for a rotor having an inside diameter of 9 inches, to provide nozzle speeds which will vary in different instances but in typical instances will be of the order of 250 to 500 feet per second. The

fluid feed material employed will vary in different instances and may contain for example one or more suspended solids, with or without one or more components in solution or as a colloid. As an example of such feed material reference can be made to starch liquor which contains finely divided starch particles in suspension with soluble carrying water, together with gluten. As this feed material is supplied to the rotor heavier centrifugally separated material is discharged from the nozzles 32, and by virtue of the absolute velocity at the time of discharge the jets of material pass outwardly through the throat passage 69 into the volute 51. With proper regulation of the discharge from volute 51, the volute and the outer portion of the throat passage 69 become filled with material, whereby a level is established which may vary somewhat with operating conditions, but which is intermediate the annular orifice 71 and the tips of the nozzles 32. As previously explained such regulation can be had by properly proportioning the passage through the orifice 56 whereby a predetermined pressure head is maintained in volute 51, and in the passages 52, 53. The material discharging from nozzles 33 is not in the form of solid streams, but is in the form of jets of somewhat dispersed material, due probably to rotary movement (about the axis of the orifices) as the material passes through the discharge orifices. Although the backward direction of these jets serves to recover considerable kinetic energy and thus reduces the power required for operation of the machine, the discharging material retains considerable kinetic energy. As the discharging material impacts the surface of material in throat passage 69, a portion of this kinetic energy is used to keep the discharged slurry in violent agitation, and a portion is transferred to the body of liquid material. As the result of such energy absorption the body of material in the throat passage has considerable rotary velocity in a direction about the axis of the rotor, and in addition there is a velocity component outwardly to cause flow through annular orifice 71 into the volute passage 51. The rotary velocity component gradually decreases in a direction toward the throat orifice 71 to effect conversion of kinetic energy to static pressure head. In passing outwardly through the annular orifice 71 into the volute passage 51 there is a further reduction in flow velocity in a radial direction with the result that there is further building up of a static pressure head in the volute passage. A very substantial pressure head in the volute passage is desirable because it enables better flow from the volute passage through the return pipe bend 53 back into the machine or through auxiliary equipment such as the flotation cell 61 of Figure 5. In addition it permits discharge of the underflow to a tank or other piece of equipment located a considerable height above the centrifuge.

In addition to the above the throat passage 69 receives the discharging material in such a fashion as to minimize back splash upon the nozzles and upon the rotor. Elimination of back splash further reduces the power requirements for operation of the machine, and in addition it minimizes the amount of material which must be returned back into the rotor for retreatment. It further reduces the possibility of centrifugally separated underflow material finding its way into the overflow. Swirling of material in throat passage 69 and also in the volute passage 51 is desirable in that in many instances it serves to re-

tain materials in relatively fluid condition, particularly where the materials have tendencies similar to thixotropic characteristics such as tend to cause an apparent increase of viscosity upon flowing in relatively quiescent condition. Thus it is possible to operate with a relatively high gravity underflow.

It will be evident from the foregoing that in the operation of the machine a novel method is employed. The material in the throat passage 69 comprises a portion of a body of material, the main part of which is in the volute chamber 51. The portion of the liquid body which is in the throat passage 69 may be said to extend inwardly in a radial direction from the main part of the liquid body, and in this inwardly extending body portion the kinetic energy of underflow material received from the nozzles is converted to hydraulic or static pressure in the main part of the liquid body.

In the embodiment of the invention illustrated in Figures 6 and 7, the throat rings 101 and 102 are altered as to dimensioning to provide the throat passage 103. In addition, the rings have flared portions 104, 105 to form the enlarged entrant portion 106. This embodiment functions in substantially the same manner as the embodiment of Figure 1 except for the more desirable proportioning.

Figures 8 and 9 illustrate a further embodiment of the invention which incorporates heat exchange means. In this instance the two housing sections 111a and 111b can be constructed similar to the sections 12a and 12b of Figure 1, except that they are provided with annular flanges 112a, and 112b. The parts 113a and 113b, which can be formed of suitable material such as sheet metal, are mounted between the flanges 112a, 112b, to form a restricted throat which is designated generally at 114. As viewed in plan the parts 113a, 113b are annularly contoured, and together with the flanges 112a, 112b, they form annular passages 116a, 116b for circulating a cooling or heating liquid. Surrounding the parts 113a and 113b, there is a volute part 117, which can likewise be fabricated of sheet metal, and which serves to form the volute passage 118. A plurality of diffusion vanes 119 are positioned between the opposed faces of the parts 113a, 113b, and the spaces between these vanes form circumferentially spaced and outwardly divergent flow passages 121. Because of the shaping and proportioning of these passages, the vanes serve to more efficiently convey the material received from the nozzles in a direction outwardly and into the volute passage 118. In so directing the material kinetic energy is more effectively and efficiently converted to hydraulic pressure, and splash-back is minimized. The inwardly faced walls of the parts 113a, 113b are so curved as to form an inwardly divergent annular zone 122 for receiving material from the nozzles 32. The parts 113a, 113b can be strengthened by providing a plurality of spaced ribs or webs 123a, 123b.

When using a construction as illustrated in Figures 8 and 9 the same return circuit and underflow draw-off connections can be employed as previously described with reference to Figure 2. However as indicated in Figure 11 it is possible to provide a special underflow draw-off which facilitates the draw-off of material at relatively high gravity. Thus in this connection two of the vanes 119a have adjacent ends which form an outwardly directed pocket 126, instead of one of the passages 121. At the outer end of this pocket

there is a passage 127 which connects to an underflow draw-off pipe. In a typical instance only one such draw-off pocket can be provided, and the remaining spaces between the vanes can be passages of the type illustrated in Figure 9. With the arrangement shown in Figure 11 it is possible to draw off starch at relatively high gravity because of the static pressure head developed in the closed pocket 126 and because under such pressure head relatively high gravity underflow material tends to flow without difficulty.

When using the starch draw-off shown in Figure 11 it is desirable to introduce wash water into the return circuit by way of a tangential pipe 130, which should be located just beyond the tangential take-off of the underflow return pipe. Introduction of wash in this manner tends to have a lubricating action in the outer part of the volute passage and aids attainment of high underflow gravity without clogging.

Figure 10 diagrammatically illustrates one way in which the chambers 116a, 116b can be connected to an external circulating system for absorbing or adding heat to the material being treated in the centrifuge. Thus in this instance a pump 128 is connected to a heat exchanger 129, and to piping whereby liquid is withdrawn from the chambers 116a, 116b, passed through the heat exchanger and then returned to these chambers. Either cooling or heating liquid can be continuously circulated through the chambers 116a, 116b, to effect an efficient heat transfer with respect to material which is passing through the general throat passage 114. By employing a suitable cooling liquid such as water, overheating of material having heat sensitive components can be avoided. By the use of a heated liquid, heat can be efficiently transferred to the underflow in order to maintain the material undergoing treatment at a desired elevated temperature. The ribs 123a and 123b can be made of good heat conducting material to assist exchange of heat between walls 113a, 113b and the heat exchange liquid. Figure 10 also illustrates a starch draw-off line 131 which leads from a closed pocket 126 and which can be valve controlled.

This application is a continuation-in-part of my copending application Serial No. 584,879, filed March 26, 1945, now abandoned.

I claim:

1. In a centrifuge, a rotor provided with a passage for introduction of feed material and also provided with nozzles for discharge of heavier separated material and a lower part forming an impeller to receive heavier discharge material and to return the same to the rotor, a housing enclosing the rotor, means carried by the housing for receiving material discharged from said nozzles, a return nozzle at the lower end of the housing and disposed beneath the lower end of the impeller and directed upwardly into the same, conduit means for returning a substantial part of the discharged material to said nozzle, whereby such discharged material is discharged upwardly into the impeller, the housing being formed to provide a space about said nozzle which is adapted to receive material which may spill into the housing from the rotor, and a pick-up ring carried by the lower end of the impeller and provided with vanes operating in said space to act upon material in said space to impel such material into the impeller.

2. In a centrifuge, a rotor arranged to operate on a vertical axis and provided with a passage

for introduction of feed material and also provided with nozzles for discharge of heavier separated material, and a lower portion forming an inverted conical shaped impeller to receive heavier discharge material and to return the same to the rotor, a housing enclosing the rotor, volute means carried by the housing for receiving material discharging from said nozzles, a nozzle at the lower end of the housing and directed to discharge material upwardly into the lower open end of the impeller, conduit means for returning a substantial part of the discharge material to said nozzle for introduction into the lower end of the impeller, the housing being formed to provide an annular space surrounding the nozzle which is adapted to receive material which may spill into the housing from the rotor, and a pick-up ring carried by the lower end of the impeller and operating in said recess, said pick-up ring having an opening aligned with the passage through said nozzle and being formed with vanes adapted to deliver material in said space into the impeller.

3. In a centrifuge, a rotor having a passage for introduction of feed material and having circumferentially spaced nozzles for discharge of heavier separated material, a structure surrounding the rotor and formed to provide an annular volute passage, said volute passage being disposed generally in a plane at right angles to the axis of rotation of the rotor, and means interposed between the inner periphery of the annular volute passage and the periphery of the rotor forming an annular throat disposed to receive material from the discharge nozzles and serving to deliver such material into a mass of the heavier separated material occupying the annular volute passage, with conversion of kinetic energy to static pressure head, said throat providing an outwardly convergent entrant portion to receive material from the nozzles and a restricted portion through which such material passes from the entrant portion to the inner periphery of the volute passage, and a plurality of circumferentially spaced diffusion vanes disposed in said restricted portion and serving to direct material outwardly into the volute passage.

4. In a centrifuge, a rotor having a passage for introduction of feed material and having circumferentially spaced nozzles for discharge of heavier separated material, a structure surrounding the rotor and formed to provide an annular volute passage, said volute passage being disposed generally in a plane at right angles to the axis of rotation of the rotor, and means interposed between the inner periphery of the annular volute passage and the outer periphery of the rotor forming an annular throat disposed to receive material from the discharge nozzles and serving to deliver such material into a mass of the heavier separated material occupying the annular volute passage, said throat providing an outwardly convergent entrant portion to receive material from the nozzles and a restricted portion through which such material passes from the entrant portion to the inner periphery of

the volute passage, a plurality of circumferentially spaced diffusion vanes disposed in said restricted portion and serving to direct material outwardly into the volute passage said throat together with said vanes forming means for converting kinetic energy of material discharging from the nozzle to static pressure head, and means for imposing a substantial pressure head on material in the volute passage to maintain the same and a portion of the annular throat filled with discharge material.

5. In a centrifuge, a rotor having a passage for introduction of feed material and having circumferentially spaced nozzles for discharge of heavier separated material, a structure surrounding the rotor and formed to provide an annular volute passage, said volute passage being disposed generally in a plane at right angles to the axis of rotation of the rotor, means interposed between the inner periphery of the annular volute passage and the outer periphery of the rotor forming an annular throat disposed to receive material from the discharge nozzles and serving to deliver such material into a mass of the heavier separated material occupying the annular volute passage, said throat providing an outwardly convergent entrant portion to receive material from the nozzles and a restricted portion through which such material passes from the entrant portion to the inner periphery of the volute passage, a plurality of circumferentially spaced diffusion vanes disposed in said restricted portion and serving to direct material through the spaces between said vanes, and from there into the volute passage, said throat together with said vanes forming means for converting kinetic energy of material discharging from the nozzles to static pressure head, the outer end of one space between two of said vanes being closed to the volute passage, means forming a passage for withdrawing underflow material from the outer end of said last named space, whereby material so withdrawn is not delivered into the volute passage, means for imposing a substantial pressure head on material in the volute passage to maintain same and a portion of the annular throat filled with discharge material, and means forming a flow conducting path for continuously returning the major portion of the separated material from the volute passage back into the rotor for re-discharge through said nozzles, said last means including a flow passage communicating tangentially with said volute passage for removal of material therefrom.
